UNITED STATES PATENT OFFICE.

FREDERICK D. WILSON AND LEONARD S. BURNS, OF OTTUMWA, IOWA, ASSIGNEES, BY MESNE ASSIGNMENTS, TO AUSTIN MANUFACTURING COMPANY, OF CHICAGO, ILLINOIS, A CORPORATION OF ILLINOIS.

ROAD-GRADING DEVICE.

Application filed July 22, 1922. Serial No. 576,703.

To all whom it may concern:

Be it known that we, FREDERICK D. WILSON and LEONARD S. BURNS, citizens of the United States, residing at Ottumwa, in the 5 county of Wapello and State of Iowa, have invented certain new and useful Improvements in Road-Grading Devices, of which the following is a specification.

Our invention relates to road grading devices, and is specially designed for use in connection with tractors and motor vehicles of a heavier type. It is of a similar character to the machine set forth in our former application for Letters Patent of the United 15 States, filed December 8th, 1921, Serial No. 520,934, the present invention being more particularly fitted and adapted for use in connection with a smaller type of tractor, such, for instance, as is known commercially 20 as the "Fordson" tractor.

One of the purposes of the present device is to provide a combined grader, leveler, and drag, or smoother, the joint operation of which will be effective in maintaining a 25 roadway in perfect condition for travel.

Another purpose of the device is to provide a sliding, or "floating" frame, which will limit the depth of operation of the grader blade, and insure a uniform action 30 thereof. Means of a flexible or yieldable character are also provided whereby the weight of the tractor can be imparted to the frame in any desired degree, to increase or decrease the amount of engagement thereof 35 with the earth, as may be desired. This means is so arranged that it may be independently applied to either side of the frame.

Another purpose of the invention consists 40 in the manner of attachment thereof to the tractor, at a point forward of the frame, so that the front end of the frame will be supported in a substantially rigid manner, but so as to permit a desired amount of freedom 45 of movement of the rear part of the frame, with relation to the earth.

Another feature of the invention consists 50 in an arrangement of compression devices for holding the grader mechanism in working engagement with the earth, which are located at a point to receive the greatest weight of the tractor.

In the drawings:

Fig. 1 is a plan view of the invention, with

parts of an associated tractor shown in 55 broken lines.

Fig. 2 is a side elevation of the same.

Fig. 3 is a detail of one of the compression devices, partly in section.

The main frame of the device consists of a 60 pair of spaced-apart runners 1 and 2, preferably of angle-plate formation, united at their forward ends by a grader-blade 3, and at their rear ends by a cross-rod 4, having a link connection with the runners at its ends, 65 so as to permit of a limited amount of elevation of one of said runners independently of the other. Near their rear ends said runners are formed into arched portions 5, from which is supported a V-shaped plate 6, by 70 means of arms 6^a. The runners are further united by cross-rods 7, providing a lateral bracing therefor. At the rear end of the runners is a bar 8, connected therewith by means of chains 9. Attached to the front 75 end of the frame is a pair of draw-bars 10, the front ends of which are connected with a coupling 11 on the lower end of a bolt 12, which comprises the pivot-bolt for the front 80 axle of the tractor, such axle being indicated at 13.

The broken line 14 indicates one of the rear wheels of a tractor, and 15 the housing of the rear axle, secured to the ends of which is a pair of racks 16 having toothed segments 17, engaged by pawls 18 on hand levers 19, fulcrumed on the racks 16, and fitted with handles 20 operatively connected with the pawls 18 in the usual manner of such devices. The levers 19 are fitted with 85 short arms 21, to which are attached hollow rods 22, in which are slidable the upper ends of rods 23, the lower ends of said rods 23 being slidable in hollow rods 24 secured to the runners 1 and 2, respectively. Interposed between the ends of the rods 22 and 24 is a coiled spring 25, and the amount of separation of such rods is limited by means of pins in the ends of the rods 23, projecting into slots 26 and 27 in the parts 22 and 24, 90 respectively. By manipulation of the levers 19 the springs 25 can be compressed, with the result that a greater amount of the weight of the tractor is applied to the runners 1 and 2. Under normal conditions little tension would be required on the springs 25, but in some kinds of earth a greater 100 amount of force will be required to maintain

the blade in proper working position. This would be the case in operating in hard or lumpy soil, in which an ordinary grader would not operate satisfactorily. The rear 5 end of a tractor is usually the heaviest, and the operator is usually stationed on the machine at a point above the rear axle, so that ample weight is provided at that point for exerting the desired amount of force on the 10 runners. The hand-levers 19 are also conveniently located for the operator's control, and are preferably arranged so as to operate in opposite directions, as shown, so that when it is desired to exert a pressure on both 15 runners at once, one of the hand-levers can be moved forwardly and the other rearwardly.

By a proper operation of the hand-levers the members 22 can be elevated until the pins in the rods 23 are in adjacent ends of the 20 slots 26 and 27, with little or no tension on the springs 25. A continued movement of the levers will operate to raise the runners 1 and 2 from the ground a sufficient distance to permit the tractor to be transported from 25 one place to another without interference by the grader. For the purpose of such transportation the bar 8 can be supported on the rear ends of the runners. It will be obvious that either of the runners 1 and 2 can 30 be raised or lowered independently of the other, and that one of such runners can be held in a more elevated plane than the other, as might be required in working on an incline, or in passing obstructions.

35 To prevent lateral movement of the rear part of the frame, and at the same time permit a vertical movement thereof, there is attached to the rear axle housing of the tractor a bracket 28, to which is fixed a plate 29, 40 having an angular portion to which is pivoted one end of a rod 30, the other end of which has a pivotal connection with the runner 2, at the upper part of the arch 5 therein.

The blade 3 is disposed diagonally of the 45 frame, and operates upon the surface of a highway in the usual manner of grading devices, except that the weight of the tractor prevents it from lifting when it encounters lumps or other inequalities of the soil. The 50 plate 6 follows after the blade 3, leveling and packing the earth in rear thereof, and following after the plate 6 is the bar 8, the purpose of which is to still further smooth the piece of roadway that is being renewed. 55 These last-named devices also assist in filling up any depressions made by the wheels of the tractor.

The extension of the runners 1 and 2 rearwardly past the plate 6 causes such plate 60 to move over the earth in a uniform manner, without digging into the same. The bolt 12 may be specially prepared, and substituted for the usual pivot bolt of the tractor.

Changes can be made in the construction 65 and arrangement of the various parts of the

machine, such as would suggest themselves to one skilled in the art to which it pertains without departing from the general scope and purpose thereof.

What we claim, and desire to secure by 70 Letters Patent, is:

1. In combination with a portable frame, a slideable frame formed of spaced apart runners, having arched portions near their rear ends; a cutting blade at the forward 75 end of said slideable frame; a leveling device supported in said arched portions; means for attachment of the forward end of said slideable frame to the forward part of the portable frame; and means for communicating the weight of the portable frame to the slideable frame, at a point between said cutting and leveling devices.

2. In combination with a portable frame, a slideable frame formed of spaced apart 80 runners, united at their forward ends by a cutting device; a leveling device near the rear ends of said runners; a drag mechanism attached to the rear end of said frame; means for attachment of said slideable frame to said portable frame; and means for imparting the weight of said portable frame to said slideable frame at a point between 85 said cutting and leveling devices.

3. In combination with a portable frame, a slideable frame having a connection with the forward part of said portable frame, and provided near its rear end with an upwardly arched portion; a cutting blade carried at the forward end of said slideable 90 frame; a leveling device supported in the arched portion of said frame; so that the lower edge thereof will be in substantially the same plane as the lower edge of the cutting blade; and means carried by said 95 portable frame for causing a yieldable engagement of said slideable frame with the earth, said means being applied between 100 said cutting and leveling devices.

4. In combination with a portable frame, 110 a slideable frame connected with the forward part of said portable frame, and provided with an arched portion near its rear end; a cutting blade carried by the forward end of said portable frame; a leveling device supported in said arched portion, so as to operate in substantially the same plane as said cutting blade; compression devices carried by said portable frame, capable of exerting a yieldable force on said 115 slideable frame, between said cutting and leveling devices; and means for increasing or diminishing the pressure of said compression devices, as desired.

5. In combination with a portable frame, 125 a slideable frame formed of spaced-apart runners; a cutting blade carried by the forward ends of said runners; a leveling blade supported by said runners at a point near the rear ends thereof; means for connection 130

- of the forward end of said slidable frame with said portable frame, near the front end thereof; compression devices carried by said portable frame, and capable of exerting a 5 yieldable force on said runners, independently of each other; means for controlling the amount of tension of said compression devices; and means for preventing lateral movement of the slidable frame with relation to the portable frame.
6. In combination with a portable frame, a slidable frame formed of spaced-apart runners having arched portions near their rear ends, and provided at their forward 15 ends with means for connection with the portable frame; a cutting blade carried at the forward ends of said runners; a leveling device supported in the arched portions of said runners; a drag having a flexible connection with the rear ends of said runners; compression devices carried by said portable frame and capable of exerting a yieldable force on said runners, independently of each other, at a point between said cutting blade 20 and leveling device; and means for controlling the tension of said compression devices.
7. In combination with a portable frame, a slidable frame formed of spaced apart runners having an arched portion near 30 their rear ends; a cutting blade carried by the front part of said frame; a leveling device carried by the arched portions of said frame; a draw-bar connection for attachment of said slidable frame with said portable frame, so as to cause a downward pull 35 on the front end of said portable frame; compression devices carried by said portable frame and capable of exerting a yieldable force on said slidable frame; and means 40 for controlling the amount of tension of said compression devices, said means being capable of elevating said slidable frame from contact with the earth.
8. In combination with a tractor, having 45 small forward carrying wheels and a pivoted axle therefor, and a pair of large rear carrying wheels and a stationary axle therefor, a slidable frame having a draw-bar connection with the pivot of such forward 50 axle, and provided with an arched portion intermediate its ends; a cutting blade carried by the forward end of said slidable frame; a leveling device supported in the arched portion of said frame; a drag having a flexible connection with the rear end 55 of said frame; controlling mechanism mounted on the rear axle of said tractor; and compression devices connecting said controlling means with said frame, capable 60 of actuating either side thereof independently of the other, or both sides thereof simultaneously, said devices being adapted to increase or diminish the force applied to said frame, or elevate the same above the 65 earth, if desired.
9. The combination of a tractor provided with a pivoted front axle; a slidable frame having a draw-bar connection with the pivot of such axle; a cutting blade and leveling device carried by said frame; and 70 controlling devices mounted on the rear of the tractor for raising and lowering said slidable frame under tension.
10. The combination of a tractor provided with a pivoted front axle; a slidable 75 frame having a draw-bar connection with the pivot of such axle; controlling devices provided with compression means mounted on the rear of the tractor which are adapted to increase or diminish the force applied 80 to said frame.
11. The combination of a tractor provided with a pivoted front axle; a slidable frame having a draw-bar connection with such axle; said frame being provided with 85 spaced apart cutting and leveling devices; and manually adjustable means attached to the rear of the tractor for applying a portion of the tractor's weight to said frame.
12. In combination with a portable frame, a slidable frame formed of spaced-apart runners; a cutting blade carried by the forward ends of said runners; a levelling blade supported by said runners at a point near 90 the rear ends thereof; means for connection of the forward end of said slidable frame with said portable frame, near the front end thereof; telescopic connecting members interposed between said portable frame and slidable frame, provided with tension 95 devices midway their ends; means for increasing or decreasing the force of said tension devices, at will.
13. In combination with an automotive vehicle, a depth gauging frame, having a plurality of rigid draft members pivotally connecting the forward end with the forward end of said vehicle, and a cutting blade, levelling bar, and drag member secured to said frame substantially as shown.
14. In combination, an automotive vehicle, a depth gauging frame, a rigid draft member pivotally connecting the forward end of said frame to the forward end of said vehicle, and dirt moving devices carried by said frame.
15. In combination, an automotive vehicle, a depth gauging frame, beneath said vehicle, a rigid draft member pivoted for vertical movement only, connecting the forward end of said frame with the forward end of said vehicle, and earth moving devices carried by said frame.
16. In combination, an automotive vehicle having front and rear wheels, a cutting blade located between said front and rear wheels, a depth gauging frame secured to and travelling in the path of said blade, and rigid draft members vertically pivoted to 125 said frame and vehicle.

17. In combination, an automotive vehicle wherein the steering and propelling of same is accomplished by the front and rear wheels respectively, a cutting blade, a depth 5 gauging frame secured to said frame and travelling only on the smooth surface made by said blade, and draft means connecting said frame and vehicle in a manner causing a downward pull on the forward end of said 10 vehicle substantially as shown.

18. In combination, an automotive vehicle wherein the steering and propelling is accomplished by the front and rear wheels, respectively, a road planing machine composed of a depth gauging frame and blade 15 operating beneath said vehicle, and draft means being so located that a downward pull is caused on the forward wheels of said vehicle to facilitate the steering of same.

19. In combination, an automotive vehicle wherein the steering and propelling is accomplished by the front and rear wheels respectively, a road maintenance machine 20 operating beneath said vehicle, draft means, said means being capable of causing a downward 25 pull on the front wheels of said vehicle and later controlling means, in the rear of the draft means connecting said vehicle and machine.

20. In combination, an automotive vehicle wherein the steering and propelling is accomplished by the front and rear wheels, respectively, a road maintenance machine composed of a depth gauging frame and 30 blade operating beneath said vehicle, connecting means, said means causing a downward 35 pull on the front wheels of said vehicle.

cle, and means for applying the desired degree of vehicle weight to said machine.

21. In combination, an automotive vehicle 40 wherein the steering and propelling is accomplished by the front and rear wheels, respectively, a road maintenance machine composed of a depth gauging frame, and blade operating beneath said vehicle, connecting means, said means causing a downward 45 pull on the front wheels of said vehicle, and manually adjustable means for transmitting pressure from the vehicle to said machine on each side thereof. 50

22. In combination, an automotive vehicle wherein the steering and propelling is accomplished by the front and rear wheels, respectively, a road maintenance machine composed of a depth gauging frame, and 55 blade operating beneath said vehicle, connecting means, said means causing a downward pull on the front wheels of said vehicle, and means provided with tension devices, for the independent control of each 60 side of said machine.

23. In combination, an automotive vehicle, a smoothing blade, a depth gauging frame secured to said blade, draft means, lateral control means, and means for applying 65 a portion of the vehicle weight to said frame between the draft and lateral control means on each side of the longitudinal center line, substantially as shown.

In testimony whereof we affix our signatures. 70

FREDERICK D. WILSON.
LEONARD S. BURNS.
